UNITED STATES PATENT OFFICE.

CLARENCE M. CORLEW, EPHRAIM SCUDDER, AND JERRY CARLETON, OF SIOUX FALLS,
SOUTH DAKOTA.

HOSE-SUPPORTER.

1,281,523.

Specification of Letters Patent. Patented Oct. 15, 1918.

Application filed April 20, 1916. Serial No. 92,409.

To all whom it may concern:

Be it known that we, CLARENCE M. CORLEW, EPHRAIM SCUDDER, and JERRY CARLETON, citizens of the United States, and residents of Sioux Falls, in the county of Minnehaha and State of South Dakota, have invented a certain new and useful Improvement 5 in Hose-Supporters, of which the following is a specification.

One of the principal objects of our invention is to provide an improved garter or hose supporter especially designed and adapted for use in connection with knee length underwear.

A further object of the invention contemplates the provision of an improved elastic hose supporter designed to connect the hose to the undergarment in such manner as to be readily and quickly attached and detached 20 without risk of lacerating or injuring the fabric, and especially designed to hold the underwear and hose in their proper relative position and without encircling the leg or otherwise causing injurious pressure thereon.

With these and other objects in view which will become apparent as the description proceeds, the invention resides in the construction, combination, and arrangement of parts hereinafter more fully described 30 and claimed, and illustrated in the accompanying drawings in which like characters of reference indicate like parts throughout the several figures, of which—

Figure 1 represents a front elevational view of the improved supporter in use.

Fig. 2 represents a detail plan view thereof.

Fig. 3 represents a view in perspective of one of the clasps.

Fig. 4 represents a view in perspective of one of the clips used in securing the clasp to the supporter.

Our present invention is an improvement on the hose supporter forming the subject 45 of Patent Number 1132395, granted to Clarence M. Corlew, dated March 16, 1915.

In carrying out our invention, we provide a supporter including an upper elastic arm A and lower diverging elastic arms B. The 50 arms are connected at their inner ends to a central polygonal, preferably five-sided web portion 5. Each of the arms consists of a pair of spaced parallel preferably elastic strips 6. At their inner ends these strips 55 are placed between the backing piece of

strong resistant material, and the facing piece of silk or other like material, which together form the web portion 5. The backing and facing pieces and inner end portions of the elastic strips, are then all stitched together, thus securely anchoring the inner ends of the strips to the web 5.

The upper arm A is somewhat longer than the lower arms and lies in such relation with them that a continuation of the upper arm 65 would bisect the angle formed by the lower arms B.

Each of the arms of the supporter is equipped at its outer end with one of the clasps 7. The construction of these clasps 70 differs from the construction of the clasps shown in the above mentioned patent only in that apices 8 of the clasps are rounded rather than pointed, and further detailed description of the clasps, it is thought, therefore, is not necessary. The clasps 7 are each connected to one of the arms by having the outer ends of the strips forming the arm bent over the members 9 of the clasps and secured in place against the strip by means 80 of the clips or bands 10 shown in Fig. 4. The bands each encircle one of the strips adjacent the clasps, looping over the overbent end of the strip, and when the bands are clenched in place, the overturned ends of 85 the strips are secured against the body portions thereof through the medium of the prongs or spurs 11 being passed through the material.

In use, as shown in Fig. 1, the lower clasps 90 7 of the supporter are attached to the hose by folding the material of the hose at the proper places and drawing the clasps thereover so that the fold will be engaged between the gripping jaws of the clasps. The upper 95 clasp is then in like manner attached to the undergarment. The supporter is arranged preferably on the outside of the leg of the wearer at about the middle of the knee. The supporter operates not only to hold the 100 hose in place with but two points of contact, but tends to draw the top of the hose more firmly about the leg, through the action of the elastic arms tending to draw the clasps carried by the lower arms toward each 105 other. The supporter also operates to hold the undergarment down in place and prevent its working upwardly on the leg of the wearer, and at the same time the supporter, in giving and allowing free play of all move- 110

ments of the leg, will afford a degree of comfort not ordinarily attained by devices of this class.

Although it is desirable that all three of the arms of the supporter be made of elastic material, it may be preferable in some instances to make one or more of them of non-elastic material. The operation of the device in the latter instance would attain the results pointed out, although not to such degree as when all the arms of the supporter are elastic.

Although we have described the preferred embodiment of our invention, we may desire to make such changes in the construction, combination, and arrangement of parts thereof, as do not depart from the spirit of the invention, and the scope of the appended claim.

Copies of this patent may be obtained for five cents each, by addressing the "Commissioner of Patents, Washington, D. C."

We claim:—

A clasp member for hose supporters, comprising a piece of wire formed to present a bar and a curved portion connecting the ends of the bar, said bar having a reentrant portion intermediate the ends of the same and forming gripping jaws lying alongside each other and approximately perpendicular to the bar, the clasp at the connected ends of the jaws being enlarged to form a loop or eye, said clasp being formed from a wire bent to shape and having its ends connected with interengaging eyes, said eyes being at one end of the bar and at the adjacent end of the curved portion.

CLARENCE M. CORLEW.
